CLAIM

The ornamental design for packaging, as shown and described.

DESCRIPTION

FIG. 1 is a perspective view of packaging showing our new design in accordance with a first embodiment of the invention;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top view thereof;

FIG. 7 is a bottom view thereof;

FIG. 8 is a perspective view of packaging showing our new design in accordance with a second embodiment of the invention;

FIG. 9 is a front elevation view thereof;

FIG. 10 is a rear elevation view thereof;

FIG. 11 is a left side elevation view thereof;

FIG. 12 is a right side elevation view thereof;

FIG. 13 is a top view thereof;

FIG. 14 is a bottom view thereof;

FIG. 15 is a perspective view of packaging showing our new design in accordance with a third embodiment of the invention;

FIG. 16 is a front elevation view thereof;

FIG. 17 is a rear elevation view thereof;

FIG. 18 is a left side elevation view thereof;

FIG. 19 is a right side elevation view thereof;

FIG. 20 is a top view thereof; and,

FIG. 21 is a bottom view thereof.

The portions of the packaging shown in broken lines form no part of the claimed design.

1 Claim, 21 Drawing Sheets
